UNITED STATES PATENT OFFICE.

EMERY JOHNSON, OF NEWBERG, OREGON.

ELECTRIC-LAMP REGULATOR.

No. 857,404.

Specification of Letters Patent.

Patented June 18, 1907.

Application filed January 25, 1907. Serial No. 354,119.

To all whom it may concern:

Be it known that I, EMERY JOHNSON, a citizen of the United States, residing at Newberg, in the county of Yamhill and State of Oregon, have invented a certain new and useful Electric-Lamp Regulator, of which the following is a specification, reference being had therein to the accompanying drawing.

This invention relates to electric lamp regulators and the object of the invention is to provide an attachment for electric lamps adapted to be connected to an ordinary lamp socket in place of the usual lamp and to support and supply the current to the lamp itself, the said regulating attachment embodying novel means whereby the current fed to the lamp may be regulated to produce in the lamp an illuminating candle power of any desired degree.

With the above and other objects in view the nature of which will more fully appear as the description proceeds, the invention consists in the novel construction, combination and arrangement of parts, herein fully described, illustrated and claimed.

In the accompanying drawings:—Figure 1 is a diametrical section through a regulator attachment embodying the present invention. Fig. 2 is a plan view of the regulator, and Fig. 3 is a diagrammatic view of the circuits.

The attachment comprises a frame or spool of non-conducting material and said frame or spool consists of oppositely arranged plates or heads of disk form, shown at 1 and 2, spaced apart a suitable distance to admit the resistance coils hereinafter referred to, and connected by a central and preferably cylindrical core 3, the frame thus resembling an ordinary reel or spool with relatively large heads.

Fastened to one of the frame pieces or heads 1 is a screw threaded metal connection 4 adapted to screw into the ordinary lamp socket, while fastened to the other frame piece or head 2 is a corresponding screw threaded metal connection 5 adapted to receive the threaded end piece of the usual lamp, the device thus forming an attachment which is interposed between a lamp and lamp socket such as are now in common use. A conductor rod or stem 6 passes centrally through the metal connection 4 and core 3 and besides holding said parts together, it carries the current from the lamp socket to the lamp. The metal connection 5 is fastened to the frame piece 2 by screws 7.

Arranged at the peripheries of the frame pieces 1 and 2 and connecting the same is a head 8 of insulating material which carries a plurality of contact points *a, b, c, d, e, f, g* and *h*, which project a suitable distance from the surface of the contact head 8. Disposed around the core 3 and between the frame pieces or heads 1 and 2, is a series of coils 10, 11, 12, 13, 14, 15 and 16, the said coils being composed of insulated wire and wrapped one upon and around the other, practically filling the space between the heads 1 and 2, while from said coils lead wires extend to the contact points *a, b, c, d, e, f, g* and *h*.

Rotatably mounted in the contact head 8 is a rod or shaft 17 having an operating knob 18 so that it may be manipulated by hand, and connected fast to said rod or shaft is a contact finger or lever 19 adapted to be moved into contact with any one of the contact points to carry the current between said point and the rod or shaft 17 which is also in the circuit. It will be understood that the coils 10, 11, 12, 13, 14, 15 and 16 are made up of insulated wire of high electrical resistance and by means of the switch described, any one or more of said resistance coils may be thrown into the circuit and opposed to the current passing through the lamp, thereby reducing to any desired extent the candle power of the lamp. The end of the line wire entering the attachment by which the current is made to pass through the resistance coils, is connected by wire 20 with the first contact point *a* of the switch and when the contact finger or lever of the switch rests on said point, the current passes through said finger to the operating rod or shaft 17 which is connected by wire 21 with the metal connection 5 which carries the current to the lamp. In this position the resistance coils are not in the circuit and the lamp has its full power. By turning the knob 18 so that the contact finger or lever rests on another point the current is caused to pass through one or more of the resistance coils and on account of the resistance offered by said coils, the illuminating power of the lamp will be correspondingly reduced. 22 designates a stop pin to limit the movement of the switch in both directions.

The attachment will ordinarily be inclosed in a suitable casing or covering. By the use of the attachment, which may be applied by any one, a great saving of current is effected and any desired candle power may be ob-

tained without a change of lamps. The device may be used with any kind of current, either direct or alternating, and will be found convenient in the sick room where a bright light is objectionable. It also renders the usual lamp useful as a night lamp by regulating the same to produce a very dim light.

I claim:

1. An electric lamp attachment adapted to be interposed between a lamp and lamp socket and to connect the same, the attachment comprising a frame consisting of oppositely arranged plates of non-conducting material, and a core connecting said plates, a series of resistance coils wrapped one upon another around said core and between said plates, and means including a switch for throwing one or more of said coils into the lamp circuit.

2. An electric lamp attachment adapted to be interposed between a lamp and lamp socket and to connect the same, the attachment comprising oppositely arranged frame plates of non-conducting material, a core interposed between said plates, resistance coils wrapped one upon another around said core and between said frame plates, a contact head connecting said plates, contact points on said head to which lead wires from the coils are connected, and means including a switch for throwing one or more of said coils into the lamp circuit.

In testimony whereof I affix my signature in presence of two witnesses.

EMERY JOHNSON.
